(57) **CLAIM**

The ornamental design for a milk stirrer as shown and described.

DESCRIPTION

1. Milk stirrer

1.1: Perspective

1.2: Perspective

1.3: Front

1.4: Back

1.5: Left

1.6: Right

1.7: Top

1.8: Bottom

1.9: Enlarged view of detail 1.9 in FIG. 1.1

The even spaced broken lines in the drawings depict portion of the milk stirrer that form no part of the claimed design. The dot-dash broken lines in reproductions 1.1 and 1.9, designating the boundary of the enlarged view, form no part of the claimed design.
